UNITED STATES PATENT OFFICE

153,607

DESIGN FOR A BILL CONTAINER

William E. Hilby, Indianapolis, Ind.

Application July 26, 1947, Serial No. 140,539

Term of patent 14 years

(Cl. D74—2)

To all whom it may concern:

Be it known that I, William E. Hilby, a citizen of the United States, residing at Indianapolis, in the county of Marion and State of Indiana, have invented a new, original, and ornamental Design for a Bill Container, of which the following is a specification, reference being had to the accompanying drawings, forming part thereof.

In the drawings, Fig. 1 is a perspective view of a bill container, showing my new design. Fig. 2 is a top plan view thereof. Fig. 3 is a section thereof taken on the line 3—3 of Fig. 1 in the direction of the arrows.

I claim:

The ornamental design for a bill container, as shown and described,

WILLIAM E. HILBY.
